(57) **CLAIM**

The ornamental design for an electronic fuel injection throttle body, as shown and described.

DESCRIPTION

FIG. 1 is a first perspective view of an electronic fuel injection throttle body showing my new design;

FIG. 2 is a second perspective of the design of FIG. 1;

FIG. 3 is a front view of the design of FIG. 1;

FIG. 4 is a rear view of the design of FIG. 1;

FIG. 5 is a top view of the design of FIG. 1;

FIG. 6 is a bottom view of the design of FIG. 1;

FIG. 7 is a right side of the design of FIG. 1; and,

FIG. 8 is a left side view of the design of FIG. 1.

The broken lines shown in the drawings are for the purpose of illustrating portions of the article and form no part of the claimed design.
